UNITED STATES PATENT OFFICE.

JOHN BEISWANGER, OF STEUBENVILLE, OHIO, ASSIGNOR TO GILL BROTHERS COMPANY,
OF STEUBENVILLE, OHIO, A CORPORATION OF WEST VIRGINIA.

DESIGN FOR A BAKING-DISH.

52,816.

Specification for Design.

Patented Dec. 31, 1918.

Application filed May 6, 1918. Serial No. 232,944. Term of patent 7 years.

To all whom it may concern:

Be it known that I, JOHN BEISWANGER, a citizen of the United States of America, and resident of Steubenville, county of Jefferson, State of Ohio, have invented a certain new, original, and ornamental Design for a Baking-Dish, of which the following is a specification.

In the accompanying drawing I have illustrated a baking-dish constructed in accordance with my invention.

Figure 1 is a side elevation of the dish; and

Fig. 2 is a bottom plan.

The dish which embodies the invention is of transparent material, circular in plan and having shallow side walls 2 which are substantially straight but flared slightly outward from the bottom. These side walls are ornamented externally with upright Doric flutes 3, shaded at the top into the rounded rim 4 which encircles the top edge. At the

bottom edges the flutes join the rounded peripheral corner surface 6 which encircles the bottom of the dish. At diametrically opposite points, the dish is provided with handles 7, shown as projecting in a horizontal plane from the rounded rim 4 which encircles the top edge.

The bottom of the dish as shown is ornamented as to its outer surface with radial flutes 8, joining the curved bottom peripheral edge surface 6.

Having thus described and illustrated my invention, I claim:

The ornamental design for a baking-dish, substantially as shown and described.

Signed by me at Steubenville, Jefferson county, Ohio, this 2nd day of May, 1918.

JOHN BEISWANGER.
